UNITED STATES PATENT OFFICE.

JULIUS SOLOMON, OF OBERLIN, OHIO.

FOOTWEAR.

Application filed December 30, 1922. Serial No. 603,803.

My invention relates to improvements in footwear, and more particularly to an improved support for footwear such as boots and shoes, the present embodiment of the 5 invention relating more particularly to an improved shoe heel and arch supporting bridge member adapted to form and reinforce the heel and shank portions of a boot or shoe so as to properly maintain and support at all times in proper normal or relative position the various bones of the foot and particularly the arch portion thereof so as to prevent any impairment or breaking down of such arch.

15 The primary object of the invention is to provide a generally improved support for footwear through the medium of improved heel and shank forming and supporting members, the heel being provided with an 20 improved arch or shank supporting bridge member in the specific form of an integral extension having its upper portion curved to conform to the normal contour of the shank portion of the shoe and having a flat tread 25 portion forming an extension of the tread portion of the heel and bridging the space between the latter and the ball portion of the shoe sole.

A further and very important object is 30 the provision of a generally improved arch and heel support for footwear which may be either formed as a part of and as a reinforcement for shoes or boots as originally manufactured, or as an auxiliary or additional appliance or attachment in lieu of the 35 ordinary arch support and as an improvement thereon.

With the above mentioned and other ends 40 in view, the invention consists in the novel construction, arrangement and combination of parts, hereinafter described, illustrated in some of its embodiments in the accompanying drawings and particularly pointed out in the appended claim.

45 Referring to the drawings, forming a part of this specification, Figure 1 is a perspective view of the underside of an ordinary shoe equipped with an attachment constructed in accordance with this invention and embodying a heel and an integral shoe shank supporting bridge member constructed and arranged in accordance with this invention.

Fig. 2, an enlarged fragmentary central vertical view of the same.

Fig. 3, a plan view of the upper or 50 outer side of the improved heel and

arch supporting bridge member detached from the shoe upper.

Fig. 4, a fragmentary side elevation of a shoe equipped with a modified form embodying an offset half heel or heel lift.

Fig. 5, a side elevation of the same, detached.

Fig. 6, a perspective view of the underside 65 of an ordinary shoe equipped with a support embodying integral heel, bridge and sole members, the latter in the present instance being slightly inset from the marginal edges of the original sole and shoe upper.

Similar numerals of reference designate 70 like parts throughout all the figures of the drawings:

The general form of the boot or shoe, except as hereinafter referred to in connection with my improved construction and arrangement of parts, may be of any suitable and convenient construction. My improvements may be incorporated in shoes of widely differing forms and types, being adaptable for use in connection with ladies' 80 shoes and with heels of different styles, as for example, relatively low heels or relatively high or French heels. The term "shoe" as hereinafter referred to is understood to include a "boot" and in which similar parts and features may be included.

The shoe may be provided with the usual shoe sole 1, with the usual arch or shank portion 1^a, and the heel receiving portion 1^b.

As a means of providing a suitable arch 90 and heel support for the foot, and particularly as a means of reinforcing the shoe and causing the same to retain its original contour or shape to properly support the foot at all times, an improved support is provided, 95 said support comprising a shoe heel 2, and an integral arch supporting bridge member 2^a. The heel 2 may be of any suitable form or type and likewise the bridge member or extension 2^a. The arch supporting extension or bridge 2^a is curved at its upper surface as at 2^b to conform to and support the shank portion 1^a of the shoe and is provided with a relatively flat tread portion 2^c, extending in a plane with and forming a continuation of the tread surface 2^d, of the shoe heel 2. The bridge or extension member 2^a is of tapered or wedge shaped form terminating in a relatively thin edge 2^e, at the ball portion 1^c of the shoe sole and may be 100 attached thereto in any suitable and convenient manner, as for example, by means

100

105

Fig. 3, an enlarged fragmentary central vertical view of the same.

Fig. 4, a plan view of the upper or outer side of the improved heel and

110

of attaching elements or tacks 2^f. The sides of the bridge or extension member may be undercut or bevelled, as at 2^g, forming a relatively narrow shank portion for coming into direct contact with the surface below. By reason of the fact that the lower tread portion of the bridge or extension comes into direct contact with the ground or other surface tread upon, it will be seen that the weight of the arch of the foot and the shank portion of the shoe are supported directly thereon, and it will also be obvious by reason of the fact that this member bridges the space between the heel shank and sole portions of the shoe, that such bridge or filler member also reinforces and connects the shank and heel portions of the shoe relative to each other.

If desired, an offset half heel or heel lift 2^b, may be provided in lieu of the full heel 2, shown in Figs. 1, 2, 3 and 6 of the drawings, and in which instance, as shown in Figs. 4 and 5 of the drawings, a shoulder 2¹, is provided to abut against the breast portion of the upper heel lifts of the shoe heel 2.

If desired, the extension or bridge member 2^a may continue into and form a part of a shoe sole 1^d, as shown in Fig. 6 of the drawings, and if desired, such shoe sole 1^d may take the form of an auxiliary sole having its edges slightly inset from the marginal edges of the main sole 1 and the shoe upper, as shown in Fig. 6 of the drawings, and particularly when applied to a lady's shoe.

The marginal edges of the heel 2 and of the bridge or filler 2^a are preferably inwardly bevelled as at 2^j to conform to the contour of the adjacent shank and heel por-

tions of the shoe and when a full sole is used the edges thereof are similarly bevelled to conform to the main sole or the shoe upper. For the purpose of lessening the weight of and the material in the improved support, the bridge or extension member 2^a may be provided with a central channel portion 2^k, terminating in a heel opening or cavity 2^l, as shown most clearly in Figs. 2 and 3 of the drawings. It should be understood also that the improved support may be made of any suitable and convenient resilient material, preferably of rubber as shown,—and that the heel and bridge members are preferably formed integral with each other.

Having thus described some of the embodiments of my invention, without having attempted to set forth all the forms in which it may be made, or all the modes of its use, what I claim and desire to secure by Letters Patent is,—

In combination with the shank portion of a shoe, a shoe heel having an integral extension forming an arch supporting bridge extending beneath said shank portion of the shoe, said shoe heel and arch supporting bridge having their tread surfaces extending flush with each other and being respectively provided with heel and channel shaped cavities on their upper surfaces, the marginal edges of said shoe heel and bridge being inwardly bevelled to conform to the contour of said shank and the heel portions of the shoe.

In testimony whereof I have affixed my signature.

JULIUS SOLOMON.
